United States Patent Office

Des. 211,380

Patented June 11, 1968

211,380

CLOCK

Dario Moranduzzo, Via Aretina 161, Florence, Italy

Filed Sept. 22, 1966, Ser. No. 3,982

Term of patent 14 years

(Cl. D42—7)

FIG. 1 is a front elevational view of a clock embodying my new design;

FIG. 2 is a top plan view;

FIG. 3 is an enlarged front and side perspective view; and

FIG. 4 is a rear view thereof.

I claim:

The ornamental design for a clock, as shown.
